(57) **CLAIM**

The ornamental design for an arm for service robot, as shown and described.

DESCRIPTION

FIG. 1 is a perspective view of an arm for service robot, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view showing the arm for service robot in a state of use;

FIG. 9 is yet another perspective view showing the arm for service robot in a state of use;

FIG. 10 is another perspective view showing the arm for service robot in a robot environment; and,

FIG. 11 is yet another perspective view showing the arm for service robot in a robot environment.

The broken lines illustrating portions of the arm for service robot and environmental structure form no part of the claimed design.

1 Claim, 11 Drawing Sheets
